UNITED STATES PATENT OFFICE.

WILLIAM F. PERSONS, OF LAKEWOOD, OHIO, ASSIGNOR TO THE GUIDE MOTOR LAMP MANUFACTURING COMPANY, OF CLEVELAND, OHIO, A CORPORATION OF OHIO.

DESIGN FOR AN AUTOMOBILE-LAMP.

48,760.

Specification for Design.

Patented Mar. 21, 1916.

Application filed March 26, 1915. Serial No. 17,273. Term of patent 3½ years.

To all whom it may concern:

Be it known that I, WILLIAM F. PERSONS, a citizen of the United States, residing at Lakewood, in the county of Cuyahoga and State of Ohio, have invented a new, original, and ornamental Design for Automobile-Lamps, of which the following is a specification, reference being had to the accompanying drawing, forming a part thereof.

Copies of this patent may be obtained for five cents each, by addressing the "Commissioner of Patents, Washington, D. C."

I claim:

The ornamental design for an automobile lamp as shown.

In testimony whereof I have affixed my signature in presence of two witnesses.

WILLIAM F. PERSONS.
